UNITED STATES PATENT OFFICE.

LÉON O. DION, OF NATICK, MASSACHUSETTS, ASSIGNOR TO JOHN M. FISKE,
TRUSTEE, OF SAME PLACE.

SHUTTER-WORKER.

SPECIFICATION forming part of Letters Patent No. 316,529, dated April 28, 1885.

Application filed November 26, 1883. (Model.)

To all whom it may concern:

Be it known that I, LÉON O. DION, of Natick, in the county of Middlesex and State of Massachusetts, have invented a certain new and useful Device for Opening and Closing Blinds and Shutters, of which the following, taken in connection with the accompanying drawings, is a specification.

My invention relates to devices for operating shutters or blinds from the interior of the house to which they are attached; and it consists in certain novel features and arrangements of parts, which will be readily understood by reference to the description of the drawings and the claims to be hereinafter given.

In the drawings, Figure 1 represents a perspective view of a window the blinds of which are provided with and operated by my improved device. Fig. 2 represents an enlarged side elevation of my improved device, the different parts of which being shown in the positions they occupy when the blinds are closed. Fig. 3 represents a front elevation of the same. Fig. 4 represents a side elevation of the same with the parts thereof in the positions they occupy when the blind is opened. Fig. 5 represents a partial sectional elevation on line *xx* on Fig. 2. Fig. 6 represents a central longitudinal section of the rotary lifter. Fig. 7 represents a sectional elevation of the blind-fastener, the cutting-plane being transverse to the window-sill; and Figs. 8 and 9 represent, respectively, a side elevation and a plan of the pintle, which is attached to the blind.

A is a window-frame of the usual construction, B is the sill thereof, and C C are blinds secured thereto by the hinges *aa*. Each blind is provided on its lower end with a suitable fastening device for retaining the blind either in an open or closed position.

The device shown in the drawings consists of a vertically-moving latch, *b*, secured by one end to the blind near its pivotal edge, while its opposite end extends through the staple-guide *c*, and is retained in the bottom thereof by virtue of its own tension. This latch *b*, when the blinds are closed, engages with the catch *d* and retains the blinds in that position, while it effects the same object when open by engaging with the catch *e*.

A little above the lower hinges *aa* suitable holes are bored through the window-frame, to each of which holes is fitted a metal tube, D, in which is mounted the shaft E, to the inner end of which—*i. e.*, that end which enters the interior of the house—is firmly secured the crank-handle F. Near the outer end of the shaft E the rotary lifter G is firmly secured thereto, so as to revolve therewith. The extreme outer end of the shaft E consists of an enlarged hub, *f*, to which is firmly secured the spiral spring H, the opposite end of which is secured to the vertical hub *g* of the removable pintle I, mounted in a suitable bearing in the ear J of the metallic bracket K, firmly secured by screws or otherwise to the blind C, the said pintle I being provided with an ear, *m*, in which is formed an angular notch, *n*, to fit the corner of the bracket K, as shown in Figs. 3, 70 and 9.

When the reduced end of the pintle I is in the bearing in the ear J, and the corner of the bracket K is within the notch *n*, and the spring H is holding the said pintle I in this position, 75 the said pintle is as rigid with the bracket K as if it formed an integral part thereof, and therefore the blind C may be readily moved about its hinges by rotating the pintle I.

The rotary lifter G is made of such a diameter that the toe *h*, mounted on its outer edge parallel to its axis, projects beneath the shoulder *i* of the bracket K, the blind being provided with a suitable cavity, *k*, to accommodate such rotation of the toe *h*. The bracket 85 K has extended from its front surface the projecting arm *l*, by which the blind may be lifted when the said blind is in an open position.

The operation of my invention is as follows: The different parts of my improved device 90 being in their normal positions, as shown in Figs. 1, 2, 3, 5, and 7 of the drawings, if the blinds are desired to be opened, the handle F is moved in the direction of the arrow, Fig. 1, thereby rotating the lifter G and bringing the 95 toe *h* thereof in conjunction with the shoulder *i* upon the blind, when, if the lifter G continues to be rotated, the blind C will be lifted upon its hinges *aa* a sufficient distance to disengage the latch *b* from the catch *d*. While 100 the blind C is being thus lifted and the shaft E rotated, the vertical pintle I is prevented from

revolving until the latch *b* is released from the catch *d* on account of the engagement of the notch *n* of the ear *m* thereof with the corner of the bracket *K* upon the blind *C*, and, therefore, as one end of the spring is being rotated with the shank *E* while the other is securely held in a fixed position, an extra torsional strain is given to the spring *H*, which, when the blind *C* has been lifted so as to disengage 10 the latch *b* from the catch *d*, causes the blind to swing outwardly. The continued rotation of the handle *F*, shaft *E*, and hub *f* causes a torsional strain to be transmitted through the spring *H* to the pintle *I*, which is thereby 15 cause to rotate in its bearing, and by virtue of the notch *n* of the ear *m*, acting upon the corner of the blind *C*, the said blind is also caused to rotate until the latch *b* engages with the catch *e*, when the blind will be retained in 20 an open position. In this position—*i. e.*, with the blinds open—the parts are in the position shown in Fig. 4, and to close the blinds the handle is turned in the opposite direction, when substantially the same operation will be 25 repeated, with the exception that the toe *h* acts upon the projection *l* to lift the blind, instead of acting upon the shoulder *i*.

If at any time it is desirable to remove the blind, it can readily be accomplished by simply 30 removing the pintle *I* from its bearing, which will sever all connections between that part of the device which is attached to the frame and that which is applied to the blind, so that the blind may be lifted from its hinges.

35 It is obvious that the connections may be as readily made again by simply placing the notched end of the ear *m* against the corner of the bracket *K* and inserting the reduced end of said pintle *I* in its bearing.

40 It is obvious that instead of a spiral spring any other flexible coupling made in a single piece (as a cylinder of rawhide) may be used to connect the shaft *E* to the pintle *I*, and that my improved lifting device may be used 45 with any other means for rotating the blind—as, for instance, a pair of bevel-gears or a ball-and-socket joint.

To operate the shutters from the interior of the house in stormy weather without the 50 necessity of opening the window has long been deemed advantageous, and therefore many attempts have been made to accomplish this object, the results of which have failed to come into general use either on account of their 55 liability of getting broken or otherwise inoperative, or on account of their complexity and cost.

To obviate these difficulties is the object of this invention.

60 One of the greatest disadvantages to be

found with devices for this purpose heretofore constructed is that their only point of fastening is on the hinged side of the blind and generally in a line with the axis of rotation of the blind, so that the wind in rough 65 weather is liable to get so great a leverage upon the blind as to tear it from its points of attachment; but in the improved device herein described this disadvantage is entirely obviated, as each blind has a fastening device 70 secured thereto at some little distance from the axis of rotation of the blind, the said fastening device being operated, as has already been described, from the interior of the house.

I am aware that a coiled spring has been 75 heretofore used for transmitting power.

What I claim as new, and desire to secure by Letters Patent of the United States, is—

1. A device for operating blinds or shutters, 80 consisting of a shaft adapted to pass horizontally from the exterior to the interior of the window-frame and provided on its inner end with means for rotating it, a support or ear adapted to be attached to the blind, and flexible coupling composed of a spiral spring rigidly secured at one end to the shaft and at the 85 other end to the ear, as set forth.

2. In a blind or shutter operating device, 90 the combination of the crank-shaft *E*, the rotary lifter *G*, the shoulder or arm *i*, and a means for connecting said shaft *E* with a vertical pintle secured to the blind *C* and adapted to transmit motion from the said shaft to the said pintle and through it to the blind, substantially as described.

3. In a blind or shutter operating device, 95 the combination of the crank-shaft *E*, the rotary lifter *G*, the shoulder or arm *l*, and a means for connecting said shaft *E* with a vertical pintle secured to the blind *C* and adapted to transmit motion from the said shaft to the said pintle and through it to the blind, substantially as described.

4. In combination with a blind or shutter pivoted by one of its vertical edges, the crank-shaft *E*, the revolving lifter *G*, the bracket *K*, with the shoulders or arms *i* and *l*, firmly secured to the pivotal edge of the blind or shutter, a flexible or universal joint connecting the shaft *E* with the bracket *K*, the latch *b*, and catch *d* or *e*, all arranged and adapted to operate substantially as described.

In testimony whereof I have signed my name to this specification, in the presence of two subscribing witnesses, on this 23d day of November, A. D. 1883.

LÉON O. DION.
